UNITED STATES PATENT OFFICE.

ADELBERT B. CASE, OF SPRINGFIELD, MASSACHUSETTS.

PAWL-AND-RATCHET DEVICE.

SPECIFICATION forming part of Letters Patent No. 435,087, dated August 26, 1890.

Application filed June 18, 1890. Serial No. 355,897. (No model.)

To all whom it may concern:

Be it known that I, ADELBERT B. CASE, of Springfield, in the county of Hampden and State of Massachusetts, have invented a new and useful Improvement in Pawl-and-Ratchet Devices, of which the following is a specification, reference being had to the accompanying drawings, forming part thereof.

My invention relates to that class of pawl-and-ratchet mechanisms in which a pawl operatively connected with and carried by a shaft co-operates with ratchet-teeth upon the inner surface of a hub embracing said shaft, to cause said shaft and hub to revolve in unison in one direction, and to permit the shaft to revolve independently of the hub in the opposite direction; and the invention has especial reference to such mechanism as applied to lawn-mowers to make the connection between the shaft carrying the wiper-knives and the pinion-gears, through which motion is transmitted from the draft-wheels to said shaft.

It is a fact well known to those who have occasion to use lawn-mowers that the part which sustains the greatest wear in such machines and which soonest requires to be repaired or renewed is the connection between the wiper-shaft and its operating-gears. With a view to overcoming this objection inside pawl-and-ratchet mechanisms have been largely adopted, said mechanisms comprising an annular recess in the bore of the pinion-gears, located midway between the ends of said bore, with ratchet-teeth extending into said recess from one or both sides thereof, and a pawl located within a longitudinal groove in the shaft and having a free sliding movement therein, which pawl, by its engagement with said ratchet-teeth in the gear, causes the latter and the shaft to revolve in unison in one direction and permits the gears to revolve independently of the shaft in the opposite direction. Various forms of pawls and ratchets to be thus used have been devised, but in all of them a single pawl is utilized to co-operate with either one or two rows of teeth. In the former case—that is to say, when the single pawl is used with a single row of ratchet-teeth—the maximum amount of lost motion resulting from a reversal of the movement of the machine is of course

the distance between the individual teeth of the series, and as but three teeth are usually employed such lost motion is considerable 55 and the wear upon the teeth and pawl very rapid. In the latter case, with two rows of teeth and those of one row alternating with those of the other, the amount of lost motion is reduced one-half; but even in such case 60 the single pawl is rapidly worn to such an extent as to seriously impair its perfect engagement with the teeth. In either case, moreover, the leverage of the pawl upon the teeth being located wholly upon one side of the 65 longitudinal center of the hub of the pinion-gear, a torsional strain upon said hub is exerted, which wears the bore thereof in such manner as to in time cause a looseness in the movement of the gear and an imperfect 70 operation of the wiper-knives. I have found that these and other objections to such previous constructions can be entirely obviated by employing, in connection with one or two rows of inside ratchet-teeth on the pinion- 75 gear, a plurality of pawls on the shaft to engage said teeth, said pawls being located at circumferentially-different points of the shaft; and my invention therefore consists of such combination and arrangement of said parts, 80 as hereinafter fully described, and particularly pointed out in the claims.

Referring to the drawings, in which like letters designate like parts in the several figures, Figure 1 is a central longitudinal section of a hub and shaft provided with a pawl-and-ratchet mechanism embodying my invention. Fig. 2 is a similar view of the hub detached from the shaft. Fig. 3 is a diagram illustrating the contour of the internal annular recess of the hub. Fig. 4 is a view in perspective and longitudinal section of the shaft and pawls. Fig. 5 is a cross-section of a shaft provided with three pawls. Fig. 6 is a diagram similar to Fig. 3, illustrating the application of my invention to a hub having two rows of ratchet-teeth. Fig. 7 is an end view of the shaft designed to be used with said last-mentioned form of hub.

The letter *a* designates a shaft, and *b* a hub 100 revolvably mounted thereon, which may be the hub of a pinion-gear as utilized to operate the wiper-shaft of a lawn-mower, or of any other form of wheel which is designed

to drive or to be driven from the shaft *a*. Midway between its ends said hub *b* is provided with an internal annular recess *b'*, into which project ratchet-teeth *b*². As shown in 5 Figs. 1, 2, and 3, said hub is provided with three of such teeth located at equal distances apart and upon the same side of the recess *b'*, while upon the opposite side of the recess and alternating with said teeth are projections *b*³, the office of which is to facilitate the proper engagement of the pawl with the teeth, as clearly described in Letters Patent No. 383,624, granted to me May 29, 1888.

The shaft *a* is provided with two longitudinal grooves *a'*, which, as shown in Figs. 1 and 4, are located at diametrically-opposite points, and which receive the bases *c'* of two pawls *c* in such manner as to permit a free sliding movement of the latter within said grooves. 15 The pawls *c* are preferably provided with one flat and two curved faces to enable them to ride freely over the teeth *b*² of the hub when the latter is revolved in one direction, and to make a firm engagement with said teeth when 20 the hub is revolved in the opposite direction, as fully explained in my said previous Letters Patent. In the construction shown and described in my said Letters Patent, however, but a single pawl is employed, and some of 25 the more serious objections incident thereto are hereinbefore specified.

By reference to the diagram shown in Fig. 3, in which the position of the two pawls relatively to the three teeth of the hub is illustrated, it will be observed that when one pawl is in operative engagement with one tooth, the other pawl is midway between two teeth, and consequently that the maximum amount of possible lost motion even with a single 30 row of teeth is but one-half the distance between two teeth, thus reducing the force of the impact of the teeth with the pawls upon a reversal of the movement of the hub by one-half. One of the main causes of the rapid 35 wear of both teeth and pawl in previous constructions is thus obviated. Moreover, the alternate action of the two pawls upon the teeth distributes the wear between the former in such manner as to more than double the effective life thereof. The results just mentioned are due to the relative arrangement of the three teeth on the hub and the two pawls located at diametrically-opposite points on the shaft. It is obvious, however, that by 40 employing a greater number of teeth on the hub, or by varying the relative positions of the grooves in the shaft, the two pawls can be made to operatively engage two teeth simultaneously instead of alternately. Such 45 an arrangement would secure a stronger engaging action between the shaft and hub, and would materially reduce the wear of both teeth and pawls, as compared with previous constructions; but as the amount of lost motion would not be reduced I prefer to employ the arrangement of said parts first described.

It is obvious that more than two pawls can

be utilized in the manner described to produce very beneficial results, and I have shown in Fig. 5 a shaft provided with three grooves 70 and three pawls located at equal distances apart therein, which, if used in connection with the hub represented in Fig. 3, would cause the three pawls to engage the three teeth simultaneously, thereby securing an exceedingly strong engagement of the hub with the shaft, which can be used to great advantage in the larger sizes of lawn-mowers and in other heavy machinery. Whatever number of pawls be employed, their relative action 75 upon the teeth of the hub can in each instance be accurately predetermined by the relative circumferential locations of the grooves *a'* in the shaft.

While, as thus far described, my invention 80 secures very important advantages as applied to a hub having ratchet-teeth upon one side of the annular recess therein, it is equally applicable to hubs having teeth upon both sides of its recess, as represented by the diagram shown in Fig. 6. In this case the teeth *b*⁴ upon one side of the recess *b'* alternate in position with those upon the opposite side thereof, and the pawls *c* are located within the diametrically-opposite grooves *a'* of 90 the shaft *a*, (shown in Fig. 7,) said pawls preferably being provided with right and left hand working-faces, and having their bases extending in opposite directions.

In this application of my invention I not 100 only secure all of the advantages hereinbefore enumerated, but I also secure the additional one of dividing the strain upon the hub equally upon opposite sides of the longitudinal center thereof, and thus obviate the torsional strain which results from the engagement of a single pawl with a tooth at one side of said center, and which is the cause of very rapid wear of the hub.

The advantages specified incident to the 110 use of a plurality of pawls are equally apparent whether the hub or the shaft be the driving medium; but they are of especial importance as applied to the pinion-gears and wiper-shafts of lawn-mowers, in which 115 the former drive the latter, because of the hard usage to which such machines are put, and because said gears and shaft sustain the brunt of the work performed by the machine.

By means of my invention, with no appreciable increase in the cost of manufacture, I am enabled to prolong the effective life of such machines more than twofold, and thereby effect a material saving in the outlay required for repairs and renewal of worn-out parts.

While I have shown and described my invention in connection with sliding pawls, it is obvious that it can be applied to the various 130 other forms of pawls which have been devised to co-operate with inside ratchet-teeth upon a hub.

Having thus fully described my invention,

what I claim, and desire to secure by Letters Patent, is—

1. The pawl-and-ratchet mechanism herein described, comprising, in combination, a hub provided with a central bore to receive a shaft, an internal annular recess located substantially midway between its ends, ratchet-teeth projecting into said recess, and a shaft adapted to occupy the bore in said hub, said shaft being provided with a plurality of pawls adapted to operatively engage the teeth on said hub, substantially as and for the purpose set forth.

2. The pawl-and-ratchet mechanism herein described, comprising a hub bored centrally to receive a shaft, and provided with an internal annular recess and with ratchet-teeth projecting into said recess in a plane substantially parallel with the axis of said hub, in combination with a shaft adapted to occupy the bore of said hub, said shaft having movably connected therewith at different points thereof circumferentially a plurality of pawls adapted to operatively engage said ratchet-teeth on the hub, arranged and operating substantially as set forth.

3. The combination, with a hub having a central bore, an internal annular recess, and ratchet-teeth projecting within said recess, as

described, of a shaft adapted to fit the bore 30 of said hub, said shaft being provided with a plurality of peripheral grooves extending parallel with the axis thereof, and with a sliding pawl located within each of said grooves and projecting beyond the circumferential 35 plane of the shaft, whereby said pawls are adapted to operatively engage the ratchet-teeth on said hub, substantially as and for the purpose described.

4. The combination, with a hub having a 40 central bore to receive a shaft, an internal annular recess located midway between the ends thereof, and a series of ratchet-teeth projecting into said recess from one side thereof, of a shaft having two longitudinal 45 grooves therein located at diametrically-opposite points thereof, and two pawls having their bases located within said grooves, respectively, and adapted to have a sliding movement therein, said pawls projecting beyond the circumferential plane of said shaft, whereby they are adapted to operatively engage said teeth on the hub, substantially as described.
